UNITED STATES PATENT OFFICE.

GEORGE GILL, OF TAUNTON, MASSACHUSETTS, ASSIGNOR TO REED AND BARTON, OF SAME PLACE.

DESIGN FOR A CAKE-BASKET.

Specification forming part of Design No. 6,380, dated February 4, 1873.

To all whom it may concern:

Be it known that I, GEORGE GILL, of Taunton, in the county of Bristol and State of Massachusetts, have invented a new and original Design for Cake-Baskets or analogous articles; and I do hereby declare the following to be a full, clear, and exact description of the same, reference being had to the accompanying drawing forming a part of this specification.

The invention consists in new designs for cake-baskets or analogous articles, their bodies, and their stands, as hereinafter described.

The figure is a perspective view.

In the drawing, A represents the body, composed of a single leaf, concaved on its upper side. B B represent two flowers reclining on the edge of large leaf A, and one on each side of a leaf, C, while between the leaves C C is a larger central leaf, D. E is a bail, composed of two bows, e e, which are held together at the top by an ornamental clamp, F, and which support on and between them two tips, F' F', at equal distances from clamp, and connected by a short bow, f. G is a stand, which has

four curved rods, brought together, or nearly so, at their points of greatest convexity, and provided with a leaf, g, at each end. Between these and near the feet is a four-armed plate, H.

Having thus described my invention, what I claim as the design is—

1. A cake-basket composed of body and stand, of the general design shown and described.
2. A single leaf concaved on the upper side, as a new design for the body of cake-baskets, as shown and described.
3. The flowers B and leaves C D, as an ornamental design, to be arranged upon large leaf A, as shown and described.
4. Four curved rods, provided with leaf at each end, and arranged in connection with plate H and with respect to one another, as a new design for the stands of cake-baskets.
5. A design for bail, as shown and described.

GEORGE GILL.
